UNITED STATES PATENT OFFICE.

CLARENCE H. ROSE, OF WATERTOWN, NEW YORK, ASSIGNOR TO THE
HITCHCOCK LAMP COMPANY, OF SAME PLACE.

DESIGN FOR A QUARTER-BEND COUPLING.

SPECIFICATION forming part of Design No. 28,572, dated May 10, 1898.

Application filed March 5, 1898. Serial No. 672,787. Term of patent 14 years.

To all whom it may concern:

Be it known that I, CLARENCE H. ROSE, a citizen of the United States, residing at Watertown, in the county of Jefferson and State of New York, have invented a certain new Design for a Quarter-Bend Coupling; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This invention relates to certain new designs for quarter-bend couplings such as are used in water-closet construction and adapted to be connected to a closet-bowl.

My design is clearly illustrated in the accompanying drawing, in which I have shown in side elevation a view of the coupling.

The design consists of a quarter-bend coup-

ling terminating at one end in a flaring portion A and continued to and merging into a shoulder at one end of the coupling, which shoulder has about its middle portion a milling, while the other end of the coupling terminates in a shoulder, about the circumference of which shoulder is also a milled band, which milled bands, as shown, in connection with the coupling, form the essential features of my design.

What I claim to be new, and desire to secure by Letters Patent, is—

The design for a coupling, substantially as hereinbefore described and illustrated in the accompanying drawing.

In testimony whereof I affix my signature in presence of two witnesses.

CLARENCE H. ROSE.
